ELECTROMAGNETIC HORN

Frederick Von Voigtlander, Adrian, Mich., assignor to Schwarze Electric Company, Adrian, Mich., a corporation of Michigan

Application January 14, 1937, Serial No. 120,485

4 Claims. (Cl. 177—7)

This invention relates to features of electric horn construction and control.

This invention has utility when incorporated in horn mounting, adjustment, connections and assembly. These utilities more specifically reside in structural adaptations to respond in manufacturing requirements with nicety of control for tone in compact set-up reliable under the vibration of motor vehicle use as to resonant means 10 and electrical connections.

Referring to the drawings:

Fig. 1 is a view of the horn from the side of the motor with the housing or cover removed;

Fig. 2 is a section on the line II—II, Fig. 1, 15 parts of the projector being broken away;

Fig. 3 is a section on the line III—III, Fig. 2, looking at the back of the magnet core from the side toward the diaphragm;

Fig. 4 is a view looking into the armature on 20 the line IV—IV, Fig. 2;

Fig. 5 is a partial section on the line V—V, Fig. 1;

Fig. 6 is a perspective view of a coil clip used with the magnet bracket assembly in Fig. 5;

Fig. 7 is a view of the stem and key sleeve assembly for mounting the armature, on the line VII—VII, Fig. 2;

Fig. 8 is a partial section view showing the armature assembly with the stem on the line 30 VIII—VIII, Fig. 2;

Fig. 9 is a detail view in perspective of contact bracket at the breaker;

Fig. 10 is a wiring diagram of the electrical control connections for this electromagnetic horn;

Fig. 11 is a fragmentary view of the terminal connections held by spring clip;

Fig. 12 is a perspective view in detail of a terminal plate as used in Fig. 11;

Fig. 13 is a side elevation of the horn at its 40 mounting; and

Fig. 14 is a detail view of the bracket in the horn mounting on the line XIV—XIV, Fig. 1.

Mounting bracket 1 has plate terminal portion engaged by rivets 2 assembling yieldable Y-lamina 3 in multiple on each side of the plate 1. These Y-lamina 3 have arms 4 (Figs. 1, 14) with registering openings 5. Spacer 6 with shoulders 7 has reduced diameter portions 8 which may be 50 snapped into register with the openings 5 in these Y-arms 4 to assemble this spacer in position to receive bolts 9 in mounting the horn into assembly set-up. These bolts 9 extend through main frame member 10 of the horn to 55 which tubular extension 11 is connected to mount

straight projector 12 or elbow projector 12' (Fig. 13) flaring to terminate in bead 13.

Oppositely from this projector 11, 12, the horn proper provides cap 14 as major housing, thrust and held into assembly position by a screw 15 so that marginal flange 16 of this cap interfits about the main frame 10 inward from flange 17 of the projector portion 11. This screw 15 has threaded assembly with U-strap bracket 18, which is snap assembled at openings 19 with the main 10 frame 10.

Adjacent the main frame 10, there is mounted flexible diaphragm 20 as a partition between the housing 14 and the projector 11, 12. Extending through this diaphragm 20 is stem 21 having on 15 the projector side of said diaphragm 20, washers 22 to space resonator having flat central section 23 with gradual taper dish 24 away from the diaphragm with more abrupt taper 25 back toward the diaphragm, with the resonator rim 26 in the 20 approximate plane, (preferably within a few hundredths of an inch of coplanar) with the central portion 23 of the resonator. Within the flat central portion 23, washer 27 as locked by split washer 28 is held by nut 29 on threaded portion 30 of the stem 21 to lock this resonator in spaced 25 assembly relatively to the diaphragm for vibrational clearance in horn operation. Against the central portion of the diaphragm 20 about this stem 21 is washer 31 having peripheral flange 32 30 away from the diaphragm 20. This washer 31 fits against collar enlargement 33 fixed on the stem 21. This collar enlargement has flattened 35 side portions 34 (Figs. 2, 3) to permit ready application of wrench in holding the stem for tightening and setting the assembly of the resonator therewith.

Adjacent this collar 33 there is tapered clearance 35 of laminae 36 comprising the core for this electromagnet. This laminated magnet core has outer legs 37 and intermediate leg 38 providing grooves or slots 39 therebetween. Additionally, there is central opening 40 through this magnet core providing a way for the stem 21 in alignment with its mounting at the diaphragm 20. This laminated electromagnet core is fixed 45 relatively to the main frame member 10 by rivets 41 (Figs. 1, 3). These rivets 41 mount ears 42 of magnet carrying brackets having upstanding portion 43 against the laminae and assembled 50 therewith by rivets 44.

In these slots 39 is located coil 45 which, as extending outward from the core, is embraced by clip 46 (Figs. 1, 5, 6) having hook extension 47 which engages with the magnet bracket 43 55

holding the core in position with the frame 10. This stem 21 as protruding from the opening 40 into the housing 14 has threaded portion 48 (Fig. 2) upon which is mounted sleeve 49 having collapsible flare head 50 with its sections spaced by grooves or slots 51 (Fig. 4). This flare head 50 may seat with laminations 52 of the armature having shrouds or side assembly portions 53 anchored or locking with the laminations 52 assembled by rivets 54. Seating with this armature oppositely from the flare head 50 is washer 55 having away from the armature laminations 52, 53, convex face 56 complemental to concave seat 57 of washer 58, spaced by leaf spring 59 from washer 60, clamped therewith by nut 61 on threaded portion 62 of this sleeve 49. This means that, upon removal of the housing 14, the nut 61 may be backed off to loosen the rockable bearing 56, 57, in assembling the armature 52 into the desired alignment for determined nicety of air gap 63 with poles of the electromagnet core. This is permitted due to clearance in practice between the washer 55 and the sleeve 49 of about $\frac{1}{20}$ of an inch.

As the nut 61 is loosened to allow the collapsible or clutch portion 50 to release from the stem 21, flattened portions 64 (Fig. 7) of the threaded portion 62 may be engaged to rotate this sleeve 49 on the stem 21 either toward or from the diaphragm, and as so rotated into the desired clearance for the air gap 63, the nut 61 may be again brought into the gripping position for holding in such clearance.

This stem 21 has reduced diameter threaded portion 65 (Fig. 2) on which is mounted nut 66 locked by nut 67. This nut 66 reacts as a bumper against insulation plate 68, thereby thrusting flexible contact arm 69 with its contact 70 away from opposing contact 71 of rigid arm 72. This is the breaker action response in the device herein. Screws 73 (Figs. 2, 11) through insulation sleeves 74 assemble with bracket 75 the spring 59 which yieldably holds the stem 21. Additionally, there is mounted on these screws 73 spacers 76 and insulation 77 about the insulation sleeves 74, mounting terminal plate 78 spaced by additional insulation 77 from complementary terminal plate 78'. Horn control switch 79 (Fig. 10) as closed may cut in energy source as battery 80 and by line 81 (Fig. 1) complete circuit to terminal plate 78. The arm 69 has solder connection to line 82 to condenser 83, say of .20 microfarad, thence by line 84 to flange 85 (Figs. 1, 9) of rigid breaker arm 72. This wiring, accordingly, places the condenser 83 in parallel with the contacts 70, 71. The plate 78 is connected by way of the contacts 71, 70, to line 86 extending to the coil 45, with circuit completed by way of line 87 therefrom to plate 78', thence by line 88 to the switch 79.

In lieu of plates 78, 78', there may be substituted therefor plates 89 (Figs. 11, 12) adapted to receive bullet-shaped conductor ends 90 of supply lines in eye portions 91 with spring hook-over portion 92 adjacent notch 93 adapted to connect the lead therefrom to the coil or condenser.

In the matter of the adjustment of the air gap 63, this it is desirable to effect accurately. The core may impact the armature. This impact is not destructive as herein disclosed for the laminations of the armature do not tend to cling to the laminations of the core. The impact is transmitted to the resonator, and for this transmission it is found in practice in the horn of

general design herein that say with the resonator slightly over three inches diameter, the air gap is desirably held to approximately .027 inch to .030 inch. It has been found that if this dimension under this control is say .032 inch, the tone 5 is subdued and when the air gap is reduced say to .025 inch, the resonator tone is increased but simultaneously there is a harsh mechanical noise therewith. The laminations as disclosed herein deaden the mechanical noise generated by the 10 striking of the armature. Furthermore, the armature is of less area laterally than the bounding portions of the field or core which avoids the armature striking rigid shroud portions of the core. The condenser in parallel with the breaker 15 points is a shunt thereabout having value as arc suppressor and also additionally important hereunder; for in this type of horn with the resonator as herein, the contact is of considerably longer interval than with, say electric air or air tone 20 type horn. To obtain the advantage hereunder, it is important there be a sharpness of response, thereby making the note clear. This end is attained by this condenser for building up strength for the current in the set-up herein. 25

The resonator herein, by its design in cooperation with the air gap and controls, has a frequency of say 2500 cycles per second. Contributing toward this efficiency is the central flat region for this resonator disk with the gradual 30 dishing away from the diaphragm into a more abrupt return toward the diaphragm. The dimensions adopted herein, and found efficient, are the disk rim outer edge to start radially inward at 20° bevel or dish away from the plane 35 parallel to the diaphragm, then a 27° slant to a radius of curvature of .26 inch for a distance of 1.125 inches from the center; the disk is 2.87 inches in diameter to the outer portion of the rim taking the 27° slant. There is less steep inward arc approximating a radius of curvature of 3.15 inches to taper inward toward the flat center, of .53 inch to .54 inch diameter. This configuration of the resonator disk makes for tonal 40 efficiency in promoting the horn operation here- 45 in. Shifting of the radial distance inward or outward of the rib or corrugation crest, even slightly, very materially affects the frequency of this resonator.

What is claimed and it is desired to secure by 50 United States Letters Patent is:

1. An electric signal device embodying a magnet, an armature, and a mounting for the armature including a first washer seated toward the armature and convex away from the armature, 55 a second complementary washer, an externally threaded sleeve having a flare portion seated against the armature opposite from the washers, and a nut rotatable relatively to the respective washers, said nut on the sleeve clamping the washers against the armature oppositely from the flare means for locking assembly at an adjusted angular position for the sleeve as to the armature in definite parallelism with the magnet. 60

2. An electric signal device embodying a magnet, an armature, and a mounting for the armature including a first washer seated toward the armature and convex away from the armature, 70 a second complementary washer, externally threaded means through the washers and armature, there being collapsible flare means seated against the armature oppositely from the washers, and a nut rotatable relatively to the respective washers, said nut being threaded to clamp 75

the washers against the armature and toward the flare means for collapsing the flare means into locking assembly at an angular adjusted position fixing the armature with the flare means in 5 definite parallelism with the magnet.

3. An electric horn having a projector and a magnet, said horn comprising a diaphragm providing a partition, mounting means for the partition to form a housing isolating the projector 10 from the magnet, an armature for the magnet, a stem fixed with the diaphragm and extending through the magnet into the housing, a sleeve on the stem having a split flare head engaging one side of the armature, complementary elements 15 forming rockable bearing providing means between the armature and stem on the other side of the armature, and locking means engaging the sleeve to clamp the bearing and armature to the sleeve.

4. An electric horn having a projector and a magnet, an armature for the magnet, said horn comprising a diaphragm providing a partition in the housing isolating the projector from the magnet, a stem fixed with the diaphragm and 5 extending through the magnet into the housing, rocking-bearing-providing means for the armature on the stem relatively to the magnet, said means including a sleeve with a flare head and a seat coactive with the head, and longitudinally-effective positioning means on the stem for the armature as to the magnet for varying the spacing between the armature and magnet, there being adjustable means for the rocking-bearing-providing means at the armature accessible in the housing independently of through the projector. 10 15
